United States Patent Office

Des. 222,410
Patented Oct. 19, 1971

222,410

TEXTILE FABRIC

Leonard C. Clementi, Huntington, N.Y., assignor to Cannon Mills Company, Kannapolis, N.C.

Filed June 9, 1970, Ser. No. 23,395

Term of patent 14 years

Int. Cl. D5—02

U.S. Cl. D92—1

FIG-1

FIG. 1 is a top plan view of a textile fabric showing my new design with the area enclosed within the dotted lines thereof corresponding to one repeat of the design.

FIG. 2 is an enlarged top plan view of one repeat of the design and corresponding substantially to that area enclosed within the dotted lines of FIG. 1.

I claim:

The ornamental design for a textile fabric, substantially as shown and described.
